(57) **CLAIM**

The ornamental design for a flush mount LED bolt head, as shown and described.

DESCRIPTION

FIG. 1 is a perspective view of a flush mount LED bolt head showing our new design;

FIG. 2 is a front view thereof; and,

FIG. 3 is a right side view thereof, the left side view, the top view, and the bottom view being identical thereof.

The broken lines in the drawings represent environmental structure and it forms no part of the claimed design.

1 Claim, 3 Drawing Sheets
